TENNIS PRACTICE DEVICE

Hector O. Conde, El Cerrito, Calif., assignor to Electronic Protection Systems, Richmond, Calif.

Filed Aug. 31, 1973, Ser. No. 393,322

Term of patent 14 years

Int. Cl. D21—02

U.S. Cl. D34—5 GT

FIG. 1 is a side elevational view of a tennis practice device showing my new design.

FIG. 2 is a front elevational view thereof.

FIG. 3 is a rear elevational view thereof.

FIG. 4 is a top plan view thereof.

FIG. 5 is a bottom view thereof.

I claim:

The ornamental design for a tennis practice device, as shown.
